ATTORNEY.

UNITED STATES PATENT OFFICE.

CORNELIUS J. BROSNAN, OF SPRINGFIELD, MASSACHUSETTS.

INTENSIFIER.

1,382,338.

Specification of Letters Patent. Patented June 21, 1921.

Application filed July 1, 1920. Serial No. 393,248.

To all whom it may concern:

Be it known that I, CORNELIUS J. BROSNAN, a citizen of the United States of America, and a resident of Springfield, in 5 the county of Hampden and State of Massachusetts, have invented a new and useful Intensifier, of which the following is a specification.

My invention relates to improvements in 10 electric intensifiers or spark-gap devices which are attachable to spark-plugs, and consists essentially of a perforated clip, a screw-threaded member attached to said clip but insulated therefrom, and provided 15 with binding means for the conductor which brings the electric current to the spark-plug with which the intensifier is associated, and means to confine the spark produced with the aid of this device so that such spark can- 20 not escape into the inclosing hood for the engine which has said spark-plug mounted thereon or therein, together with such other parts and members as may be necessary or desirable in order to render the device com- 25 plete, all as hereinafter set forth.

It is a fact well known to those skilled in the art that the intensity of the spark produced when a current of electricity is passed through a spark-plug is materially in- 30 creased by forming in the circuit back of such spark-plug a spark-gap, and the primary object of my invention is to provide such a spark-gap, and to utilize as one of the spark-gap forming members a clip such 35 as is commonly used to connect the conductor or wire from the source of electrical energy with the spark-plug. By thus utilizing the clip I am able to produce an intensifier which is very simple in construc- 40 tion, convenient, and comparatively inexpensive. The efficiency of the clip is in no wise decreased, when the same is utilized as an element in my intensifier, inasmuch as it can without difficulty be connected with 45 the conductor and attached to the spark-plug.

A further object is to provide an intensifier which is safe, inasmuch as the spark produced thereby cannot escape therefrom 50 into the engine hood.

Other objects and advantages will appear in the course of the following description.

I attain the objects and secure the advantages of my invention by the means illustrated in the accompanying drawings, in which—

Figure 1 is a side elevation of an intensifier which embodies a practical form of my invention, showing the same connected with a spark-plug, the upper portion only of which appears, however, as being sufficient for the present purpose; Fig. 2, a central, vertical section through said intensifier; Fig. 3, a top plan of the clip, and, Fig. 4 a top plan of the lowermost insulating mem- 60 ber of the device.

Similar reference characters designate similar parts throughout the several views.

In the first view is illustrated the upper portion of a spark-plug, such portion con- 70 sisting of the upper terminal of a porcelain 1, the corresponding portion of a central electrode 2, a pair of nuts 3 mounted on said electrode above said porcelain, and a cap 4 between which latter and the upper nut 3 75 is received the conductor for the electric current which supplies the spark-plug. Said conductor, or that part of the same di- rectly involved in this invention, in the present case, and in very many cases, con- 80 sists of a metallic clip, as 5.

The clip 5 may vary more or less in construction, so long as it is adapted to be connected with the spark-plug, and to enter as an element into the structure of my intensifier. In the present case the clip 5 has in one terminal thereof an opening 6 to receive the upper end of the electrode 2, when the cap 4 is removed from said electrode, and an opening 7 in the other terminal. 90 The clip 5 is attached to the spark-plug by placing it on the upper nut 3, with the central electrode 2 in the opening 6, while the cap 4 is disconnected from said electrode, and then replacing said cap on said electrode 95 and screwing the same down tightly on top of said clip. A good electrical contact is thus formed between said clip and electrode.

In addition to the clip 5, the intensifier consists, in its present embodiment, of a 100 screw 6 positioned with its head downward; a metallic washer 9 on said screw above said head; a perforated disk 10 of insulating material also on said screw and between said washer and the under side of 105 said clip, which latter is placed in position after said disk is placed in position, the opening 7 in said clip permitting this to be done; a thin disk or washer 11 of insulat- 110 ing material on said screw above said clip; a hollow, cylindrical member 12 of glass or other suitable insulating material (prefer-

ably the former) on said last-named washer, said member surrounding the adjacent portion of said screw and forming an insulating cage for the sparks; a metallic washer 5 or perforated disk 13 having on the underside a washer or perforated disk 14 of insulating material, these parts also being mounted on the screw and said disk 14 bearing on top of said member or cage 12; a 10 nut 15 threaded to the screw above said disk 13; and a binding nut 16 threaded to the screw above said first-named nut. A conductor or wire, which is represented at 17 in Fig. 1, is received between the nuts 15 and 16, and held securely therebetween when said nut 16 is tightened on said wire, so that a good and sufficient electrical connection is insured between said wire and the 15 screw 8.

20 The diameter of the opening 7 in the clip 5 is considerably larger than the diameter of the screw 8, and the disk 10 has on the upper side thereof a perforated boss or hub 18 which enters said opening and fills the 25 whole or a part of the space between the edges thereof and the adjacent sides of said screw. Thus it is seen that the current, passing through the wire 17 to and through the screw on its way to the clip 5, is 30 interrupted by reason of the fact that said screw is entirely insulated from the clip 5 by the insulating members 10, 11, 12 and 14, the distance between the screw 8 and the edges of the opening 7 in said clip, 35 however, is not so great as to prevent the current from jumping or sparking across the gap, when it continues on through said clip to the central electrode 2 of the spark-plug. In spanning the gap, of which men- 40 tion has just been made, to complete the circuit, the current forms a spark and this tends greatly to intensify the spark formed or produced at the lower or inner end of the spark-plug, as hereinbefore stated or 45 intimated.

The disk 10 with its hub 18 is of sufficient thickness to prevent any possibility of the spark escaping therethrough in a downward direction, and should the spark escape upwardly through the washer 11, as is usually the case, it is received in the cage 12 and confined therein and thus prevented from coming into contact with any surrounding gases which might be inflammable or combustible. The primary object of the washer 11 is to provide a cushion or seat for the bottom of the cage 12.

The parts and members confined between the head of the screw 8 and the nut 15 are 60 tightly and securely held together by means of said nut when the latter is screwed down into place. If it be desired for any reason to disassemble the intensifier, it can be easily done simply by removing the nuts 16 and

15 and separating the parts below from each 65 other and said screw.

In practice, the intensifier, after being first connected with the wire or conductor, may be and is attached to and detached from the spark-plug at will, all in the manner 70 hereinbefore described in detail.

When the cage 12 is made of glass the spark can be seen therein, so that means is thus afforded for ascertaining at all times whether or not the intensifier is functioning 75 satisfactorily.

More or less change may be made in the shape, size, construction, and arrangement of some or all of the parts of this device without departing from the spirit of my invention or exceeding the scope of what is 80 claimed.

What I claim as my invention, and desire to secure by Letters Patent, is—

1. An intensifier comprising a metallic 85 clip which is adapted to be attached to a spark-plug, a screw-threaded member extending through said clip and provided with attaching means for a conductor, and means to attach said member to said clip, and to insulate the same therefrom so that a spark-gap is formed between said member and said clip.

2. The combination, in an intensifier, with a perforated metallic clip adapted to be connected with a spark-plug, of a screw passing through the perforation in said clip and provided with means for attachment thereto of a conductor, the arrangement being such that a spark-gap is formed between said 95 clip and said screw, an insulator located on said screw on one side of said clip, and insulating means located on and surrounding said screw on the other side of said clip, said insulator and insulating means, with 100 said clip, being confined between the head of said screw and said conductor-attaching means.

3. The combination, in an intensifier, with a perforated metallic clip adapted to be connected with a spark-plug, of a screw passing through the perforation in said clip, and provided with means for attachment thereto of a conductor, an insulator located on said screw on one side of said clip, and having a 115 thickened part to enter said perforation, and insulating means located on said screw on the other side of said clip, whereby said screw is insulated from said clip and a spark-gap is formed therebetween, said insulator and insulating means with the clip, being confined between the head of said screw and said conductor-attaching means.

4. An intensifier comprising a metallic 120 clip which is adapted to be attached to a spark-plug, a screw-threaded member extending through said clip and provided with attaching means for a conductor, and means

to attach said screw to said clip, and to insulate the same therefrom so that a spark-gap is formed between said member and said clip, said attaching and insulating means consisting in part of a cage.

5. The combination, in an intensifier, with a perforated metallic clip adapted to be connected with a spark-plug, of a screw passing through the perforation in said clip, and 10 provided with attaching means for a conductor, the arrangement being such that a spark-gap is formed between said clip and said screw, a metallic washer and an insulating disk mounted on said screw on one 15 side of said clip, a cage mounted on the other side of said clip and surrounding the adjacent portion of said screw, an insulating washer interposed between said cage at one end and said last-named side of said clip, 20 and an insulating disk over the other end of said cage, said insulating disks, cage, and clip being confined between the head of

said screw and said conductor-attaching means.

6. The combination, in an intensifier, with 25 a perforated metallic clip adapted to be connected with a spark-plug, of a screw passing through the perforation in said clip, and provided with means for attachment thereto of a conductor, the arrangement being such 30 that a spark-gap is formed between said clip and said screw, an insulator located on said screw on one side of said clip, and insulating means located on and surrounding said screw on the other side of said clip, said 35 means consisting in part of a cage, and said insulator and insulating means, including said cage, and with the clip, being confined between the head of the screw and said conductor-attaching means.
